UNITED STATES PATENT OFFICE.

JEROME T. SMITH, OF SCOTLAND, SOUTH DAKOTA.

WATER-HEATER.

1,099,519.

Specification of Letters Patent.

Patented June 9, 1914.

Application filed August 19, 1912. Serial No. 715,931.

To all whom it may concern:

Be it known that I, JEROME T. SMITH, a citizen of the United States, residing at Scotland, in the county of Bonhomme and State 5 of South Dakota, have invented a new and useful Water-Heater, of which the following is a specification.

This invention relates to water heaters, its object being to provide a fire box the wall 10 of which is hollow so as to contain water, there being a boiler supported above the fire box so as to overhang the grate of the stove, said boiler being connected to the interior of the fire box by pipes which also serve to 15 support the boiler.

Another object is to provide means whereby the hot products of combustion are caused to circulate along the inner and outer faces of the fire box and through and out 20 side of the boiler so as thus to raise the temperature of the water to the highest possible degree.

With the foregoing and other objects in view which will appear as the description 25 proceeds, the invention resides in the combination and arrangement of parts and in the details of construction hereinafter described and claimed, it being understood that changes in the precise embodiment of 30 the invention herein disclosed can be made within the scope of what is claimed, without departing from the spirit of the invention.

In the accompanying drawings the preferred form of the invention has been shown.

35 In said drawings:—Figure 1 is a vertical transverse section through a water heater having the present improvements combined therewith. Fig. 2 is a vertical longitudinal section through the water heater, the smoke 40 pipe being shown in elevation except at its lower end. Fig. 3 is a section on line A—B. Fig. 1. Fig. 4 is a section on line C—D. Fig. 2.

45 Referring to the figures by characters of reference 1 designates the base of a stove, the same constituting the ash box and having a grate 2 thereabove surrounded by an apertured ledge 3. A smoke pipe 4 extends upwardly from the base at a point back of 50 the ledge and is provided, at a point above the base, with a branch pipe 5 which opens into the upper portion of the stove casing 6, said casing extending around the ledge 3. A damper 7 may be arranged in the branch 55 pipe 5 for the purpose of controlling the passage of products of combustion from the

upper portion of the casing 6 and into the smoke pipe 4. Mounted on the ledge 3 and between the grate 2 and the openings in the ledge is a fire box 7' having a hollow wall 60 for containing water, there being feed pipes 8 opening into this hollow fire box so as to direct water thereinto from any suitable source. This fire box is removably mounted on the ledge 3 and may be formed with an 65 arch 9 in the front portion thereof and directly back of a clinker door 10. Grate teeth 11 may extend downwardly from the top of the arch, as shown, so as to retain fuel within the fire box and prevent it from 70 escaping through the clinker opening when the door 10 is open.

Extending upwardly from the fire box 7' are water conducting pipes 12 which serve 75 to support a boiler 13. This boiler is preferably cylindrical and is arranged directly over the grate 2. Flues 14 extend through the boiler from the bottom to the top thereof and the top of the boiler is spaced from the top of casing 6 so that products of combustion, after passing through the flues 14 will be free to flow between the boiler and the top of casing 6 and thence downwardly 80 within the casing to the openings in the ledge 3. An outlet pipe 15 extends from the top of the boiler and is adapted to convey 85 the hot water to the point of use.

For the purpose of preventing the escape 90 of the products of combustion between pipes 12, a sheet metal band or shield 16 is extended around the lower end of the boiler 13 and rests on the top of the fire box 7'. This band 16 may be provided with an opening 17 surrounded by flanges 18 extending up to the fuel door 19.

In order to prevent air from passing directly from the door of the ash box to the lower end of the smoke pipe 4, a partition 20 is arranged within the ash box between the front door thereof and the opening 3. 100 Thus the air entering the ash box from the door necessarily passes upwardly through the grate, through the flues 14, and, if the damper 7 is closed, necessarily downwardly 105 to the openings 3 and thence out through the pipe 4.

From the foregoing description it will be apparent that the fire box 7', pipes 12, and boiler 13 are constantly full of water. When fuel is consumed on the grate 2, the 110 hot products of combustion will pass upwardly along the inner surface of the fire

box 7', along the pipes 12, and through the flues 14, thus raising the temperature of the water. After leaving the flues 14, the combustion products flow downwardly with-
5 in the casing 6 and pass through the open-
ings in the ledge 3 and thence into the ash
box after which they flow into the smoke
pipe 4. Thus the products of combustion
serve not only to heat the interior surface
10 of the fire box 7' and the walls of the flues
14, but also serve to heat the outer surfaces
of the boiler and the fire box. Consequently
a considerable saving of heat is effected and
the temperature of the water is more quickly
15 raised than would otherwise be the case.
It will be noted that the entire water heat-
ing portion of the stove can be easily placed
in or removed from position within the cas-
ing 6, it being unnecessary to utilize any
20 means for fastening the fire box or the boiler
to the stove casing.

What is claimed is:—

In a water heater the combination with a
grate, of a fire box extending therearound
and thereabove and having a hollow wall 25
constituting a water container provided with
an inlet and an outlet, an endless band ex-
tending above and supported solely by the
fire box, a boiler closing the upper end of the
space surrounded by the band, and pipes 30
connecting the interior of the fire box to the
interior of the boiler to support the boiler,
said pipes overhanging the grate and ex-
tending into the path of the combustion
products within the band. 35

In testimony that I claim the foregoing
as my own, I have hereto affixed my signa-
ture in the presence of two witnesses.

JEROME T. SMITH.
